US0D1075604S

(12) **United States Design Patent** (10) **Patent No.:** **US D1,075,604 S**
(45) **Date of Patent:** **** May 20, 2025**

(54) **FENDER PANEL FOR AUTOMOBILES**

(71) Applicants: **Hyundai Motor Company**, Seoul (KR); **Kia Corporation**, Seoul (KR)

(72) Inventors: **Yun Jeong Lee**, Gyeonggi-do (KR); **Kyung Ryun Shin**, Seoul (KR)

(73) Assignees: **Hyundai Motor Company**, Seoul (KR); **Kia Corporation**, Seoul (KR)

(**) Term: **15 Years**

(21) Appl. No.: **29/889,887**

(22) Filed: **Apr. 18, 2023**

(30) **Foreign Application Priority Data**

Feb. 6, 2023 (KR) 30-2023-0004257

(51) **LOC (15) Cl.** **12-16**

(52) **U.S. Cl.**

USPC **D12/181**; D12/184
